TEMPLATE FOLLOWER

James L. Anderson, Closter, N. J., assignor to
Air Reduction Company, Incorporated, New
York, N. Y., a corporation of New York

Application July 10, 1937, Serial No. 152,958

17 Claims. (Cl. 33—23)

This invention relates to template-followers.

It is an object of the invention to provide an improved template-follower which automatically follows templates of irregular shape including curves of relatively short radii. The invention comprises novel features and combinations of elements which make the template-follower simple and economical to manufacture and convenient to use.

- 10 In accordance with one feature of the invention a follower roller on an inclined axis rests on the top face of a template and is driven to cause it to travel along the template, and guide means are provided for causing the follower roller to stay on the top face of the template around curves in either direction as well as along straight runs. Another object of the invention is to prevent the guide means from binding against the sides of the template on sharp curves.
- 15 20 Other objects, features and advantages of the invention will appear or be pointed out as the specification proceeds.

In the accompanying drawing, forming part hereof:

25 Fig. 1 is a sectional view of a template-follower embodying the invention.

Fig. 2 is an elevation of the lower part of the template-follower of Fig. 1, looking toward the right.

30 Fig. 3 is a fragmentary sectional view similar to Fig. 1 but showing a modified form of the invention.

Figs. 4 and 5 are elevations of other modified forms of the invention.

35 The template-follower shown in Fig. 1 has a bracket 10 with a screw 11 for clamping it to a bar 12 of a universal cutting machine. With machines having folding parallelogram frames the torch is supported from the front bar and partakes of the same movement as a tracer or template-follower clamped to the bar. The invention is not limited to machines of the folding parallelogram type, however, and the bar 12 is representative of a universal cutting machine frame which is to be moved in accordance with the outline of a template.

40 The bracket 10 has a vertical tubular bearing 14 through which a sleeve 15 extends. The sleeve 15 is free to slide up and down in the bearing 14 for a limited distance but is prevented from turning by a rack 17 which is fastened to the sleeve by screws 18 and extends into a slot 19 in the bracket 10. This slot is in effect a keyway and the rack 17 a key to prevent the sleeve from rotating, but the slot 19 is longer

than the rack so that the sleeve can move up and down. A pinion 21, on an axle 22 rotated by a hand-wheel 23, meshes with the rack 17 and serves to lower and raise the sleeve 15 when the template-follower is to be moved into or out of contact with a template. The upper part of the template-follower is similar to known tracers and a description of it is not necessary for a complete understanding of this invention. Tracers of such construction are shown in Patent No. 10,205,975, dated November 3, 1936, and Patent No. 1,999,855, dated April 30, 1935.

The lower end of the sleeve 15 is of reduced diameter and extends into a housing or frame 25. The upper end of the frame 25 has a sloping annular face which contacts with an undercut shoulder 26 on the sleeve. The housing or frame 25 rotates on the sleeve 15 as a bearing and the outside of the upwardly extending end of the frame 25 forms a continuation of the outside surface of the sleeve 15 which slides in the bearing 14. During operation of the template-follower the sleeve 15 and frame 14 are free to move up and down with a floating action in response to any irregularities in the supporting surface along which the template-follower runs.

A template-follower roller 27 is secured to the end of a sloping axle 28 that rotates in anti-friction bearings 29, 30 held by the frame 25. A bevel gear 32 keyed to the axle 28 near its upper end meshes with a bevel gear 33 fastened to the lower end of a drive shaft 35.

The frame 25 and sleeve 15 are held assembled by a collar 36 on the drive shaft 35. This collar supports a ball bearing 38 in which the shaft 35 turns, and the ball bearing thrusts against a shoulder 34 in the frame 25 and keeps the upper end of the frame in contact, or substantially so, with the undercut shoulder 26 of the sleeve.

The axis of rotation of the frame 25 about the sleeve 15 is coincident with the axis of the drive shaft 35, and the point of traction of the roller 27 on a template 37 is in line with the axis of the shaft 35.

The roller 27 is prevented from running off the top face of the template 37 by guide means which includes a lower guide roller 39, at the end of the axle 28 in position to contact with one side of the template, and two other guide rollers or wheels 40 that contact with the other side of the template. The guide roller 39 is preferably integral with the roller 27 and axle 28 but may be an idler rotatable independently of the roller 27 and axle 28. In any event some slippage of the periphery of the guide roller 39 on the side of the

template will occur because the different points on the surface of the guide roller are not equidistant from its axis of rotation and therefore travel at different velocities when the guide roller turns. This slipping is not objectionable, however, because the guide roller does not support the weight of the template-follower and has relatively light contact with the template.

The wheels 40 are preferably idlers and are supported by screws 41 from a swivel member 42 which turns about a vertical screw 44 threaded into the oblique bottom face of a rod 45. That part of each of the screws 41 just above the head of the screw comprises the axle for the wheel 40 supported by that screw, and the large flat head of each screw 41 serves as the thrust bearing which supports the weight of the wheel 40. Rotary means driven by power can be employed in place of the wheels 40, but the additional traction obtained in this manner is unnecessary with most machines on which the template-follower of this invention is used.

The rod 45 slides longitudinally in an inclined bore in the frame 25 but is prevented from turning by a pin 47 which is fixed to the frame 25 and extends through a slot 48 in the rod 45. A coil spring 50 is pressed against the upper end of the rod 45 by a screw 51 which threads into the upper end of the bore in which the rod 45 slides. The pressure of the spring 50 yieldably holds the wheels 40 against the side of the template, and the reaction of the spring against the screw 51 acts through the frame 25 and urges the guide roller 39 against the template.

One of the wheels 40 contacts with the template a short distance ahead of the point of traction of the roller 27 on the template, and the other wheel 40 touches the template some distance behind the point of traction. The distance between the wheels 40 is made short so that the template-follower can turn curves of short radii. The spring 50 makes it possible for the wheels 40 to move either way, depending upon whether they are on the inside or outside of a curve, to allow for the curvature of the arc of the template between the wheels 40. The guide roller 39 has line contact with the template along a vertical line and therefore does not bind when passing around sharp curves, as is the case with ordinary flanged wheels.

A slight speeding up or slowing down of the template-follower of Fig. 1 occurs when it turns sharp curves because of the epicyclic effect when the gear 32 rolls around the driving gear 33. The epicyclic effect causes the speed of the template-follower to increase when the gear 32 rolls in the same direction that it is turning, and to slow down when the gear rolls in the opposite direction. This variation in speed is not enough to be objectionable with ordinary work, but when very uniform speed is essential it can be obtained with the structure shown in Fig. 3.

The upper, broken away portion of the template-follower shown in Fig. 3 is the same as that shown in Fig. 1, but in Fig. 3 a frame 25' is slightly different in shape from the frame 25 of Fig. 1 to allow for a different location of bearings. Wheels 41' are supported from a swivel member 42' at the end of a rod 45' which slides in the frame 25'. The parts in Fig. 3 that correspond with parts in Fig. 1 are indicated by the same reference character with a prime appended.

A worm 54 at the lower end of a drive shaft 35' drives a worm gear 55 secured to a shaft 56

journaled in the frame 25'. A bevel gear 58 on the shaft 56 meshes with a gear 59 at the upper end of an axle 28' to transmit rotation of the shaft 56 to the axle 28'.

Ball bearings 29' and 30' hold the axle 28' at 5 an inclination and there are a traction roller 27' and a guide roller 39' at the lower end of the axle. When turning sharp curves with the modified form of the invention shown in Fig. 3 there is substantially no epicyclic effect to increase or decrease the speed of the roller 27'. If the frame 25' makes a turn of ninety degrees, the only movement of the gear 58 caused by the turning is a rotation through an angle corresponding to one-quarter of the distance between teeth of the 15 worm gear 55, and the angular movement of the rollers 27' and 39' is only slightly more, depending on the ratio of the gears 58, 59.

Fig. 4 shows a modified roller assembly which makes it unnecessary to have the wheels 40 to 20 keep the traction roller on the template. In addition to a traction roller 62 and a guide roller 63 corresponding to the rollers 27 and 39, respectively, of Fig. 1, another guide roller 65 is connected with the axle in position to contact 25 with the side of the template remote from the roller 63. Since the guide roller 63 prevents the traction roller 62 from running off the template to the left and the guide roller 65 prevents the traction roller from running off to the right, 30 the wheels 40 are no longer necessary.

Fig. 5 shows a template 69 which has a groove along its top face, and a traction roller 71 runs in this groove as shown in the drawing. This groove gives the roller greater friction contact 35 with the template, and it keeps the roller from being displaced laterally of the template when the follower is not in operation. When the roller 71 is driven to cause the follower to travel along the template, the frame and other structure to 40 which the template-follower is connected and for which it furnishes the motive power has friction in its bearings and offers resistance to the movement of the template-follower. As a result of this resistance the gear 32 (Fig. 1) tends to rotate around the driving gear 33 to turn the frame 25 about its axis. Such a turning of the frame would cause the roller 71 (Fig. 5) to climb out of the groove in the template 69, but such movement of the traction roller is prevented by a 45 guide roller 73 which is similar in construction to the guide rollers 39 and 63 employed with the embodiments of the invention shown in Figs. 1 and 4.

It will be understood that terms of orientation 55 used in the description and claims are relative. The invention is not limited to the embodiments illustrated and some features can be used without others without departing from the invention as defined in the claims.

I claim:

1. A template-follower for a universal cutting or welding machine including in combination a roller for contact with a template, an axle about which the roller turns, said axle having a 65 substantial inclination so that the roller tends to travel transversely of the template, a frame holding the axle, and a bearing on which the frame rotates, about an axis in line with a point of contact of the roller on the template, to change 70 the direction of travel of the template-follower.

2. In a template-follower, a frame rotatable about a vertical axis to steer the template-follower, an axle carried by the frame, a roller on the axle in position to contact with a template 75

- at a point in line with the axis of rotation of said frame, the axle being at a substantial, acute angle to the vertical so that the roller tends to travel toward one side of the template, and a 5 guide roller connected with the first roller in position to contact with a side of the template when the first roller is operating along the top face of the template.
3. In a template-follower, a frame and a bearing 10 on which the frame turns as the template-follower changes its direction of travel, an inclined axle carried by the frame, a template-follower roller on the axle in position to contact with the top of a template at a point in line with the axis of rotation of the frame, a second roller 15 on said inclined axle in position to contact with one side of the template and serve as a guide to confine movement of said template-follower roller transversely of the top face of the template, and means for holding the second roller against the template.
4. In a template-follower, a frame and a bearing 20 on which the frame turns as the template-follower changes its direction of travel, an inclined axle carried by the frame, a template-follower roller on the axle in position to contact with the top of a template at a point in line with the axis of rotation of the frame, and two guide rollers on the axle in position to contact with opposite sides of the template to prevent displacement of the template-follower roller transversely of the template.
5. In a template-follower for cooperation with a template having a longitudinally recessed top 25 face, a traction roller having a face which fits into the recess of the template, an axle for said traction roller, the axle being inclined with respect to the template so that the traction roller tends to climb out of the recess toward one side of the template, and a guide roller connected with the traction roller in position to contact with the other side of the template to prevent the roller from moving out of the recess.
6. A template-follower including a traction 30 roller which runs on the top face of a template, a guide roller attached to the traction roller in position to contact with a side of the template and prevent transverse displacement of the traction roller, and yielding means which hold the guide roller against the template.
7. A template-follower including a traction 35 roller which runs on the top face of a template, a guide roller attached to the traction roller in position to contact with a side of the template and prevent transverse displacement of the traction roller, a second guide roller which contacts with the other side of the template, and yielding means for urging said second guide roller against the side of the template.
8. A template-follower including a traction 40 roller constructed and arranged to travel along the top face of a template and having a guide roller directly connected with the traction roller and located in position to contact with one side of the template at a set distance from the traction roller, two wheels in positions to contact with the side of the template away from the guide roller at points slightly ahead of and slightly behind the line of contact of the traction roller and its guide roller with the template, and means urging the wheels toward the guide roller to hold said wheels and guide roller in contact with opposite sides of the template.
9. A template-follower comprising a frame, an 45 axle carried by the frame, a traction roller on the axle in position to contact with and travel along the top face of a template and having a guide roller attached to the traction roller in position to contact with one side of the template, two wheels in positions to contact with the side 5 of the template away from the guide roller at points slightly ahead of and slightly behind the line of contact of the traction roller and its guide roller with the template, a support for said wheels, and a swivel connection between said support and the frame.
10. In a template-follower, a vertical drive 10 shaft, a frame, a bearing on which the frame turns about the axis of the drive shaft, an inclined axle in the frame, a template-follower 15 roller on the axle with the low point of the roller in line with the axis of rotation of the frame, said axle having a substantial inclination so that the roller tends to travel transversely of the template, guide means for preventing transverse 20 movement of the roller on the template, and motion transmitting connections between the drive shaft and the roller.
11. In a template-follower, a vertical drive 25 shaft, a frame, a bearing on which the frame turns about the axis of the drive shaft, an inclined axle in the frame, bearings in the frame in which said axle rotates, a roller secured to the axle at a location which puts the lowest point of the roller in line with the axis of rotation of the frame, said axle having a substantial inclination so that the roller tends to travel transversely of the template, guide means which prevent the roller from running transversely and which hold 30 said roller on the top surface of the template, 35 and gearing connecting the drive shaft with the axle.
12. In a template-follower, a vertical drive 35 shaft, a frame, a bearing on which the frame turns with respect to the drive shaft and about the axis of the drive shaft as the template-follower changes its direction of travel, an inclined axle in the frame, bearings in the frame in which said axle rotates, a roller secured to the axle at a location which puts the lowest point 40 of the roller in line with the axis of rotation of the frame, said axle having a substantial inclination so that the roller tends to travel transversely of the template, guide means which prevent the roller from running transversely and which hold 45 said roller on the top surface of the template, and gearing connecting the drive shaft with the axle, said gearing including a worm on the drive shaft operating a worm wheel which has its axle supported by the frame.
13. A template-follower including a traction 50 roller supported for rotation about an axis which has a substantial inclination, means for maintaining the roller in contact with a template and the incline of the axis in a definite relation to 55 the template, said incline being sufficient to make the roller tend to move transversely of the template, and apparatus for driving the traction roller.
14. A template-follower including a frame, a 60 bearing on which the frame turns about a substantially vertical axis, an axle held in the frame, a traction roller on the axle constructed and arranged to contact with a template, said axle having a substantial inclination so that the roller 65 tends to travel transversely of the template, means holding the traction roller against transverse movement with respect to the template and holding the frame against turning except in accordance with turns in the template, and power 70 75

means connected with the traction roller for rotating said roller.

15. A template-follower including a frame, a bearing on which the frame turns about a substantially vertical axis, an inclined axle held in the frame, roller means on the axle in position to contact with a supporting surface and with an upstanding side of the template, said axle having a substantial inclination so that the roller tends to travel transversely of the template, and means connected with the frame in position to contact with the side of the template opposite to that with which said roller contacts to hold the roller against the template and keep the frame from turning except in accordance with turns in the template.

16. An automatic template-follower including a roller having a face which bears against a guid-

ing surface of a template, and having a friction face constructed and arranged to bear against a surface which is at an inclination to the axis of rotation of the roller to produce a tractive force having a component toward the guiding surface of the template, and power means for rotating the roller.

17. In a template-follower, an inclined axle, and a roller on the axle with two contact faces in such relation that one face rolls along an upstanding guiding edge of a template while the other face supports the roller from a substantially horizontal surface and supplies tractive force to the template-follower with a component of the tractive force urging the roller toward the guiding edge of the template. .

JAMES L. ANDERSON.
